CLAIM

The ornamental design for a portion of a front edge of a combination stun gun and flashlight, as shown and described.

DESCRIPTION

FIG. 1 is a front perspective view of a portion of a front edge of a combination stun gun and flashlight, showing our new design;

FIG. 2 is a rear perspective view of FIG. 1;

FIG. 3 is a front elevational view of FIG. 1;

FIG. 4 is a rear elevational view of FIG. 1;

FIG. 5 is a right-side elevational view of FIG. 1;

FIG. 6 is a left-side elevational view of FIG. 1;

FIG. 7 is a bottom plan view of FIG. 1;

FIG. 8 is a top plan view of FIG. 1; and,

FIG. 9 is an enlarged front perspective view of FIG. 1, taken along line 9 of FIG. 1.

The broken lines showing a remaining portion of the combination stun gun and flashlight in the figures depict environmental matter and form no part of the claimed design.
